UNITED STATES PATENT OFFICE.

MAURICE EDWARD STAGG SECKER, OF LONDON, ENGLAND.

WIRE-BOUND BOX.

1,382,323.

Specification of Letters Patent. Patented June 21, 1921.

Application filed April 1, 1920. Serial No. 370,597.

To all whom it may concern:

Be it known that I, MAURICE EDWARD STAGG SECKER, a subject of the King of England, residing in Catford, London, England, have invented certain new and useful Improvements in Wire-Bound Boxes, of which the following is a specification.

This invention is for improvements in or relating to wire-bound boxes, and is particularly applicable to that type of box which is commonly used as a packing for two or more tins of petrol. In such boxes the sides are generally made of thin or ply wood, each side consisting of one or more strips of wood secured together. These strips are generally held by battens and it is found that cases so formed are readily damaged in transit, and moreover are generally seriously damaged when the case is opened, as the nails used in closing the sides down are frequently clenched over and in any case the withdrawing of nails splinters the thin wood from which the case is constructed. In boxes according to the present invention, these objections are overcome, and a strong box which may be utilized time after time is provided.

The use of the invention as applied to a packing case for petrol tins is only given by way of example, and not by way of limitation.

According to the present invention a wire-bound box of the type having one or more single wires, each of which is applied to the box so as to constitute two substantially parallel binders for a side member thereof is characterized by the fact that the portion of each said wire which bridges between the binders is a long longitudinal span extending clear of the box structure and acting at or near each end as one element of a hinge for wire loops on another side member while the two ends of said single wire also extend clear of the box structure and are shaped to engage a binding wire or wires on an adjacent side member, for example the lid.

Preferably a wire-bound box according to this invention is characterized by the fact that each of three of the side members of the box has individually applied to it one or more single wires each of which consti-

tutes two substantially parallel binders both of which extend transversely across from one edge to an opposite edge of the said side member with that portion of the wire which bridges between the binders being a long longitudinal span situated near to and free of one of the edges of the side member to constitute at or near each end one element of a hinge for another side member, and one or both of the two end portions of the wire which extend to or beyond the opposite edge being shaped to engage a binding wire or wires of an adjacent side member.

The parallel portions of the binding wires preferably take the place of the battens hereinbefore referred to, though, if desired, they may be used in conjunction with such battens.

In one preferred construction the substantially parallel portions of the aforesaid single wire extend around and are secured to three side-members of the box.

In another construction each of the three side-members of the box has a single wire applied to it in the manner hereinbefore described, the end portions of the wire on one side-member being connected to the hinged side portion of the wire of an adjacent side-member. Other features of the invention will be more clearly understood from the following description taken in connection with the accompanying drawings in which—

Figure 1 is a perspective view of one form of box, (showing the box structure in skeleton with the wire in full) with the lid raised;

Fig. 2 is a similar view to Fig. 1 showing the lid closed and secured in place;

Fig. 3 is a similar view to Fig. 1 of a modified construction of box, and

Fig. 4 shows a box blank for four of the sides of the box shown in Fig. 3.

Like letters indicate like parts throughout the drawings.

Referring to the construction illustrated in Figs. 1 and 2 a box is shown having three sides 1, 2 and 3, a lid 4 and ends 5. The latter are preferably stiffened and strengthened by the provision of battens 6. To the sides 1, 2 and 3 a single wire is applied in such a manner that starting from one end 10 se-

cured to the side 1, the wire then passes at 11 transversely across the side 2 and at 12 transversely across the side 3, the parts 10, 11 and 12 being substantially in a plane 5 parallel with the box ends. The wire is then carried at a small distance beyond and free of the top edge of the side 3 in a part 13 and terminates in portions 14, 15 and 16 10 similar and parallel to the portions 10, 11 and 12 respectively. At the two ends 10 and 16 the wire is formed into loops by bending the end of the wire back onto itself and securing that end to the side 1, the loops being bent outwardly slightly from the side 15 1. These loops form means for securing the free ends of the wire of the lid to be hereinafter described. These free ends are shown at 20 and are each projections from a separate wire which passes completely across 20 the outer side of the lid at 21 and back along the underside of the lid at 22, the looped portions between the arms 21 and 22 which outstand from the edge of the lid 4 being passed around the part 13. The latter 25 constitutes one element of the hinge for the lid while the loops between the parts 21 and 22 form the other elements thereof.

It will be seen therefore that a single wire is applied to the three sides 1, 2 and 3 in 30 such a manner as to provide two parallel binders, a hinge-element and fastener-element for the lid wires.

The sides 1, 2 and 3 may, if desired, be secured together by nailing or otherwise as 35 may be found desirable, and the ends 5 may be let into grooves or rabbets formed in the inner faces of the sides 1, 2 and 3. In whatever manner the sides and ends are connected together it will be seen that a box is provided 40 having a hinged lid which may be readily and quickly secured in its closed position by means of the wires 20 and loops 10 and 16. Moreover, when it is desired to open the box it is only necessary to bend back the 45 turned-over portions of the ends 20 to free the lid so that no damage is done to it as with light packing cases having nailed-down lids hitherto employed. The manner of fastening of the ends 20 in the loops 10 50 and 16 is shown in Fig. 2 and such a fastening is readily adapted to the application of a lead or other seal to the doubled-back portion of the ends 20 in order to detect tampering or other unauthorized opening of the 55 case.

The wires as shown may be used in the place of the customary strengthening battens or in addition to the battens in which latter case they serve as a reinforcement to 60 the battens in strengthening the packing case.

In the construction shown in Figs. 3 and 4, each of the sides 1, 2 and 3 and the lid 4 65 has applied to it a single wire separate from the wire on an adjacent side. Thus on the

side member 1, the wire constitutes two looped ends 30 with a bridging portion 32 between them which is spaced away slightly from the edge of the side 1 and which constitutes one member of a hinge 70 for the wire ends on the adjacent side-member 2. The wire on the side-member 2 comprises two parallel arms 40 (secured to its outer surface) which are doubled around to loop over the portion 32 and are 75 secured as shown at 41 to the inner surface of the side-member 2. The connecting portion 42 between the two parallel binders 40 constitutes the hinge for loops provided by similar binding wires 50, 51 on the side-member 3, and as before, the connecting portion 52 between the two arms 50 are engaged by loops formed by the two parts 60 and 61 of two similar wires on the side-member or lid 4. The outer ends 62 of the 85 wires 60 provide free ends for engagement with the loops 30 in order to secure the box lid in the closed position as described in connection with the construction shown in Figs. 1 and 2.

It will therefore be seen that with this construction again each of the sides is provided with two parallel binding wires which serve to strengthen the structure and which afford hinge members for another side or 90 lid, so that to open the box it is only necessary to turn back the ends 62 to disengage them from the loops 30 when the lid will be free to open.

The ends 5 may conveniently be provided 10 with tenons sliding in corresponding mortises in the sides 1 and 2 and preferably the tenons and mortises are so formed as to constitute dove-tailed joint as illustrated. With such a construction battens similar to the battens 6 shown in Figs. 1 and 2 may be provided to strengthen the ends if desired.

It will be understood that the sides 1, 2 and 3, can be secured to the ends 5 by other means than those illustrated, for example by 11 lightly nailing them together or securing them in any other convenient manner.

Instead of forming the loops 10 and 16 or the loops 30 in the manner illustrated, they may be formed by carrying the ends nearer 11 to the top edge of the side 1, then bending them at right-angles and stapling them to the side-member after buckling them to provide loops as illustrated in dotted lines at X in Fig. 3.

It is obvious that the invention admits of many modifications without departing from the spirit or scope of the invention. For example, for larger boxes, two or more sets of wires such as those described may be applied 12 side by side to the various side-members, each set constituting parallel binders, hinge elements and one or more loops or catches. Moreover, wire according to the present invention could be applied as a reinforcement 13

to existing boxes whereof the side-members are nailed or otherwise secured together with or without wood battens.

What I claim as my invention and desire 5 to secure by Letters Patent is:—

1. A wire-bound box having applied to a side member thereof a binding-element which (a) is in the form of a single length of material constituting two substantially parallel 10 binders, (b) has a portion bridging between said binders in the form of a long longitudinal span extending clear of the box-structure and acting in the region of each of its ends as a hinge-element for another box-member, 15 and (c) has its two free ends extending clear of the box-structure and shaped to engage a binding element on an adjacent box-member, combined with a second hinge-element and a binding element at other parts of 20 the box-structure to engage respectively with the span and the free ends aforesaid.

2. A wire-bound box comprising a side member having spaced binding elements secured thereto, said elements being formed 25 from a single length of material having a long longitudinally extending span portion bridging them in the region of one edge of said side, and a lid having spaced binding elements secured thereto and projecting beyond 30 the opposite sides of the lid, the projecting portions of said binding elements at one side of the lid being adapted to engage with said longitudinally extending span portion approximately at each end of it, and at 35 the opposite side with spaced binding elements on an adjacent side member, substantially as described.

3. A wire-bound box, comprising a side having spaced binding elements secured 40 thereto, said elements being connected by a longitudinally extending span portion and having their free ends adapted to engage binding elements on another portion of the box, and a lid having spaced binding elements secured thereto and projecting beyond 45 the opposite sides of said lid, certain of the projecting portions of said last mentioned binding elements being adapted to engage said longitudinally extending span portion 50 approximately at each end thereof, substantially as described.

4. A wire-bound box having applied to a side member thereof a binding element, comprising a single length of material constituting 55 two substantially parallel binders connected by a portion bridging said binders, said portion being in the form of a longitudinal span extending clear of the box structure and serving as a hinge element for another box member, the free ends of said 60 material extending clear of the box structure and shaped to engage a binding element on an adjacent box member, and a second hinge element and binding element at other 65 parts of the box structure to engage with

said span approximately at each end thereof, substantially as described.

5. A wire-bound box having applied to a side member thereof a binding element comprising a single length of material constituting two substantially parallel binders connected by a portion bridging said binders, said portion being in the form of a longitudinal span extending clear of the box structure and serving as a hinge element for another box member, the free ends of said binders extending clear of the box structure and shaped to engage a binding element on an adjacent box member, and a lid having a binding element engaging with said span, substantially as described. 70

6. A wire-bound box having applied individually to each of three contiguous side members thereof a binding element, comprising a single length of material constituting two substantially parallel binders extending transversely from one edge to an opposite edge of its side member, and a portion bridging said binders, said portion being in the form of a longitudinal span extending near to and free of one of the edges of its side member and serving as a hinge element for another side member, said binders having their free ends formed to engage with the span of an adjacent side member 85 90 to constitute a hinged connection therebetween, substantially as described.

7. A wire-bound box having applied individually to each of three contiguous side members thereof a binding element comprising a length of material constituting two substantially parallel binders extending transversely from one edge to an opposite edge of its side member, a portion connecting said binders, said portion being in the form of a longitudinal span extending near to and free of one of the edges of its side member and serving as a hinge element for another side member, at least one of the free ends of the binding element of one of the 100 contiguous side members being shaped to engage a binding wire of an adjacent side member, and the said free ends of the binding elements of two others of the contiguous side members being engaged with and hinged 105 on the spans respectively on adjacent side members, and a fourth side element having on it a hinge element and engaging device to engage respectively with the span and free ends of the adjacent side members 110 on either side thereof, substantially as described. 115

8. A wire-bound box having applied individually to each of three contiguous side members thereof a binding element comprising a length of material constituting two substantially parallel binders extending parallel from one edge to an opposite edge of its side member, a portion bridging said binders in the form of a longitudinal span 120 125 130

extending near to and free of one of the edges of its side member and serving as a hinge element for another side member, said binding element having at least one of its free ends shaped to engage a binding wire of an adjacent side member, and a lid member also having binding elements extending

therereacross and engaging at one edge said free ends and at the opposite edge engaging the span of an adjacent side member, substantially as described. 10

In testimony whereof I affix my signature.

MAURICE EDWARD STAGG SECKER.
